US0D1075560S

(12) **United States Design Patent** (10) **Patent No.:** **US D1,075,560 S**
(45) **Date of Patent:** **** May 20, 2025**

(54) **DECORATIVE FIGURINE**

(71) Applicant: **LOUIS VUITTON MALLETIER,**
Paris (FR)

(72) Inventor: **Deyan Hristov**, Paris (FR)

(73) Assignee: **Louis Vuitton Malletier**, Paris (FR)

(**) Term: **15 Years**

(21) Appl. No.: **29/921,314**

(22) Filed: **Dec. 15, 2023**

(30) **Foreign Application Priority Data**

Jun. 19, 2023 (FR) 20232788

(51) **LOC (15) Cl.** **11-02**

(52) **U.S. Cl.**

USPC **D11/158**; D21/604
